SECRETARY OF WAR OF THE UNITED STATES OF AMERICA, IN TRUST.

METHOD OF RELINING CANNON.

1,309,163.

Specification of Letters Patent.

Patented July 8, 1919.

Application filed January 9, 1919. Serial No. 270,338.

(FILED UNDER THE ACT OF MARCH 3, 1883, 22 STAT. L., 625.)

To all whom it may concern:

Be it known that I, NATHANIEL C. WALPOLE, major, Ordnance Dept., United States Army, a citizen of the United States, stationed at Watervliet Arsenal, have invented 5 an Improvement in Methods of Relining Cannon, of which the following is a specification.

The invention described herein may be 10 used by the Government, or any of its officers or employees in prosecution of work for the Government, or by any other person in the United States, without payment of any royalty thereon.

15 This invention relates to an improvement in the method of relining cannon, and has for its object to render the process more expeditious and considerably cheaper.

In all of the methods of relining cannon 20 heretofore used the friction between the liner and the tube due to shrinkage pressure by which the liner is held, has been relied upon for the most part to prevent rotation, slipping and mandreling of the 25 liner in the tube. Some additional means of securing the liner and tube in their proper relative positions has, however, been found necessary and it has been the practice to mill one or more radial grooves in the 30 breech end of the cannon, extending through the liner and tube to the jacket. In this groove a key was securely fitted and held in place by one or more screws.

Due to the stresses between the liner and 35 the tube, developed in firing, the older methods have failed. The intense heat of the powder gases following the projectile causes the bore to expand and the thin liner is heated to a much higher temperature, and 40 therefore expands more than the mass of the tube. As the hot gases sweep by the tube cools more rapidly than the liner, and contracting, grips the metal of the liner. This prevents the metal of the liner which 45 has expanded more than the tube, from returning to its original positions, as, when the liner cools the contraction of the tube holds the ends and the liner then stretches, becoming thin in the middle. The liner is 50 also stretched by mandreling of the shell which causes movement of the metal toward the nozzle. This stretching occurs when the shell is near the muzzle at a point be-

yond which the resistance of the shrinkage pressure on the liner and the resistance of the heated metal of the liner are less than the impact and pull of the shell on the liner. As a result the liner creeps and protrudes from the breech and muzzle ends shearing off the keys at the 55 breech, and rapid failure of the liner results due to the stretching and thinning in the middle. A very slight protrusion in the breech end, also will sufficiently jam the breech mechanism to put the gun out of 60 65 action.

In the improved method the liner is forced 70 into the cannon and instead of being keyed to the tube, a form of electric welding is introduced to secure the liner against movement under the stress of firing. This method offers a much greater resistance to shearing than those heretofore used, the resistance being great enough to prevent entirely any motion of the liner relative to the 75 tube. The welds at the ends of the liner transmit the stress due to the greater expansion of the liner, to the tube, and effectually prevent any creeping or protrusion of the 80 ends. This causes the liner to be put under compression during firing and this compression is resisted by tension in the tube. No permanent distortion of the liner results and the ordinary erosion is all that it must 85 resist. This has been proven by tests under 90 which relined guns stood up as well as or better than new guns. In the preferred 95 form of invention the liner is pressed into place in the tube and then secured by welding, thereby eliminating the shrinkage operation of other methods.

This allows the complete finishing and rifling of the liner before insertion into the tube, whereas, in the older methods using shrinkage, the liner must be rifled after it is 100 in place in the tube due to the distortion and injurious effects of heating. The importance and advantages of being able to finish the liner before it is placed in position in the gun will be obvious. This allows liners to be 105 finished at a properly equipped base and then sent into the field for use, thus eliminating the necessity of returning a cannon to the base for relining. A saving of fully seventy per cent. in the time necessary to reline a gun is thus effected by this method which

is the only one known permitting the complete finishing and rifling of liners before insertion into the tube. Although the method of welding may also be applied where the shrinkage operation is used, the additional advantages obtained through securing the liner without resorting to the injurious heating of the shrinkage operation will be apparent to one skilled in the art. In the welding operation the heat is applied locally and the temperature rise even close to the weld is entirely negligible.

The object and advantages of this invention are attained by applying the method as shown in a preferred form in the accompanying drawing in which:

Figure 1, is a view of a cannon partially broken away showing the breech and muzzle ends in section.

Fig. 2, is a fragmental section of the breech end.

Fig. 3, is a fragmental section of the muzzle end.

In the drawing 1 is the jacket of a cannon and 2 is the tube. Liner 3 is preferably pressed into position in tube 2, but shrinkage can be used. Annular groove 4 is turned partially in the tube and partially in the liner as shown. Groove 4 is then filled with metal 5 by the electric welding process thereby joining the tube and liner securely. The surface is then properly machined. In a like manner groove 4 is turned in the muzzle end and filled with metal 5.

To reline, the welded metal portions are bored out, the old liner can then be forced out and easily replaced by a new liner. This eliminates the excessive wear on the tube due to the means necessary in removing liners secured by the older methods and the life of the cannon is therefore greatly increased.

While electric welding is the preferred

means for securing the liner in place, it is to be understood that any form of welding or permanently securing the liner in place and against creeping may be resorted to without departing from the scope of the invention.

Having shown and described an embodiment of the preferred form of my invention, I claim:

1. The method of securing semi-finished liners in cannon by welding.

2. The method of securing finished and rifled liners in cannon by welding at the breech end.

3. The method of securing finished and rifled liners in cannon by welding at the muzzle end.

4. The method of securing finished and rifled liners in cannon by welding at the breech and muzzle ends.

5. The method of securing liners in cannon by a welding heat locally applied.

6. The method of securing liners in cannon by electric welding.

7. The method of securing liners in cannon, which consists in first placing the liner, in an unheated condition, in the cannon, and then applying a welding heat to weld the same to the cannon.

8. The method of securing liners in cannon, which consists in first pressing the liner into place in the cannon tube, and then applying a welding heat to weld the liner to the tube.

9. The method of securing liners in cannon, which consists in first placing the liner, in an unheated condition, in the cannon, and then applying a welding heat localized in a certain area or zone of the liner, to weld the liner to the cannon.

10. A cannon provided with a liner welded therein.

NATHANIEL C. WALPOLE.
